UNITED STATES PATENT OFFICE.

CLAUD HENRY, OF EDGEWOOD, ARKANSAS.

TELEGRAPH APPARATUS.

1,130,901.

Specification of Letters Patent.

Patented Mar. 9, 1915.

Application filed December 6, 1913. Serial No. 805,071.

To all whom it may concern:

Be it known that I, CLAUD HENRY, a citizen of the United States, residing at Edge-
mont, in the county of Cleburne and State of
Arkansas, have invented new and useful Im-
provements in Telegraph Apparatus, of
which the following is a specification.

This invention relates to improvements in
telegraph apparatus and has particular ap-
plication to a telegraph receiving instru-
ment.

In carrying out the present invention, it
is my purpose to provide a telegraph receiv-
ing instrument which will be in the nature
of a combined sounder and tape marking de-
vice and whereby the tape will be marked in
accordance with the operation of the
sounder thereby producing a permanent rec-
ord of the messages received.

It is also my purpose to provide a receiv-
ing instrument of the class described which
will embrace the desired features of sim-
plicity, efficiency and durability and which
may be installed and maintained at a mini-
mum expense.

With the above and other objects in view,
the invention consists in the construction,
combination and arrangement of parts here-
inafter set forth in and falling within the
scope of the claims.

In the accompanying drawings; Figure 1
is a top plan view of a telegraph instrument
constructed in accordance with my present
invention. Fig. 2 is a view in side elevation
thereof. Fig. 3 is a longitudinal sectional
view therethrough. Fig. 4 is a transverse
sectional view of the same. Fig. 5 is a detail
view showing the control device for the mo-
tor.

Referring now to the accompanying
drawings in detail, the numeral 1 designates
a base board constructed of any suitable ma-
terial and of any desired outline. Suitably
secured to the base board 1 adjacent to one
end thereof is an appropriate form of tele-
graph sounder 2 connected in the line in the
usual manner. Upstanding from the base 1
adjacent to one side of the sounder is a post
3 slidably receiving a sleeve 4 depending
from the under surface of a table 5. Inter-
posed between the upper end of the post 3
and the bottom of the table 5 is a coiled ex-
pansion spring 6 forming a resilient support
for the table. A vertical standard 7 is se-
cured to the base 1 adjacent to the post 3

and has pivotally connected thereto an arm
8 carrying at its outer end a yoke 9 disposed
above the table 5. A leaf spring 8' has one
end fastened to the standard 7 and the oppo-
site end bearing upon the under edge of the
arm 8, such spring holding the arm 8 nor-
mally elevated. Pivotally connected to the
limbs of the yoke 9 and disposed between the
same is a self-feeding or fountain pen 10
having the pointed end thereof disposed in
proximity to the upper surface of the table.
Projecting upwardly from the upper ex-
tremity of the pen is a shank 11, while
formed integral with the adjacent end of the
armature of the sounder and offset upwardly
therefrom is an arm 12 formed with an ap-
erture 13 receiving the upper end of the
shank 11. Encircling the shank 11 is a
coiled expansion spring 14 having the lower
end thereof abutting the shoulder formed at
the juncture of the shank with the pen and
the upper end resting against the adjacent
surface of the arm 12.

Projecting upwardly from the base 1 upon
one side of the table 5 and spaced apart in
parallelism are standards 15, 15 carrying
adjustable tension rollers 16, 16, while upris-
ing from the base 1 in advance of the stand-
ards 15, 15 are bearings 17, 17 in which is
rotatably mounted a drum 18 carrying a
tape *t*. At the opposite side of the table 5 is
arranged a spring motor 19 connected with
a winding drum 20 alining with the tape
carrying drum 18, such motor being pro-
vided with a suitable form of governor 21.

From the foregoing description taken in
connection with the accompanying draw-
ings, the construction and mode of operation
of my invention will be readily apparent.
In practice, the tape *t* is passed through the
tension rollers 16 over the table 5 between
the upper surface of the latter and the pen
10 and secured to the winding drum 20. The
spring motor is now set in operation so that
the tape is drawn across the table. In the
downward movement of the sounding ham-
mer to produce the dots and dashes the arm
12 actuates the pen 10 downwardly so that
the point thereof engages the traveling tape
t whereby the dots and dashes are marked
upon the tape in accordance with the opera-
tion of the sounder, the spring 14 acting as
a shock absorber in the operation of the
sounder.

If desired, the motor may be under the

control of an electrically operated releasing device 22 connected in the sounder circuit and normally holding the motor against operation, such releasing device being actuated 5 to release the motor when the circuit through the sounder is closed.

While I have herein shown and described one preferred form of my invention by way of illustration, I wish it to be understood 10 that I do not limit or confine myself to the precise details of construction herein described and delineated, as modification and variation may be made within the scope of the claims without departing from the spirit 15 of the invention.

I claim:

1. In a telegraph receiver, the combination with a sounder, of a vertical standard disposed adjacent to one end of the armature 20 of said sounder, an arm pivoted to said standard adjacent to the upper end thereof, a yoke on the outer end of said arm, a marking device pivotally connected to the limbs of said yoke and disposed between the same, 25 a connection between said marking device and the armature of said sounder whereby the marking device will be operated in the operation of the sounder, and means for

feeding tape across the path of said marking device. 30

2. In a telegraph receiver, the combination with a sounder, of a vertical standard disposed adjacent to one end of the armature of said sounder, an arm pivoted to said standard adjacent to the upper end thereof, 35 a yoke on the outer end of said arm, a marking device pivotally connected to the limbs of said yoke and disposed between the same, the end of the armature of said sounder adjacent to said marking device being offset 40 and formed with an aperture, a shank on the upper end of said marking device projecting through said aperture, a spring surrounding said shank and forming a yieldable connection between the armature and 45 marking device whereby the marking device will be operated in the operation of the sounder, and means for feeding tape across the path of said marking device.

In testimony whereof I affix my signature 50 in presence of two witnesses.

CLAUD HENRY.
